UNITED STATES PATENT OFFICE.

JOHN W. EMERSON, OF PHILADELPHIA, PENNSYLVANIA.

DOOR SECURER.

Application filed February 9, 1924. Serial No. 691,582.

To all whom it may concern:

Be it known that I, JOHN W. EMERSON, a citizen of the United States, residing at Philadelphia, in the county of Philadelphia and State of Pennsylvania, have invented 5 certain new and useful Improvements in Door Securers, of which the following is a specification.

My invention relates to door securers 10 which are particularly adapted for use in locking doors where locks and keys are not provided. The object is to provide a door securer which may be carried in the pocket and be easily applied by a person traveling 15 about from place to place; a door securer which will positively stay in locked position and secure the door to the jamb, and which is simple and durable in construction.

This object, and other advantageous ends 20 which will be described hereinafter, I attain in the following manner, reference being had to the accompanying drawings in which

Figure 1 is a front elevation of a door 25 and door jamb having my improved door securer applied thereto,

Figure 2 a horizontal section through the door and jamb showing the door securer as it is applied for securing the door to the 30 jamb.

Referring to the drawings, 1 indicates a door jamb, 2 the door, 3 my improved door securer which is composed of a jamb member 4 provided with spikes 5 and a shoulder 35 6 which are adapted to engage the door jamb. The spikes 5 dig into the side of the door jamb while the shoulder 6 abuts the front of the door jamb. A locking member 7 has one end hinged to the jamb member 40 at 8 and is provided with a notch 9 adjacent the hinge 8. The other end 10 of the locking member abuts the door and holds it in a closed position.

A U-shaped catch 11 is pivoted to the 45 jamb member at 12 and is adapted to swing into engagement with notch 9. The catch is preferably made from a U-shaped spring wire and its pivotal connection is made by drilling holes 13 at opposite sides of the jamb member and inserting bent ends 14 of the spring wire therein.

To apply my improved door securer in 50 position to secure a door to the jamb, the device is placed between the door and jamb as shown in Figure 2. The door is then closed in the usual manner. This movement

will force the spikes of the jamb member into the door jamb and the shoulder into abutment with the front of the jamb. The locking member is then swung into its locking 60 position and the catch swung on its pivot and snapped into notch 9. The door is then rigidly secured to the jamb.

A door securer constructed as above described may be conveniently carried in the 65 pocket; may be easily applied to any door jamb and will not be unlocked by jars or vibrations of the door.

While I have described my invention as taking a particular form, it will be understood 70 that the various parts may be changed without departing from the spirit thereof, and hence I do not limit myself to the precise construction set forth, but consider that I am at liberty to make such 75 changes and alterations as fairly come within the scope of the appended claims.

Having thus described my invention, what I claim as new and desire to secure 80 by Letters Patent is:—

1. A door securer including a jamb member provided with spikes for engagement with a door jamb; a locking member hinged to the jamb member and having a notch 85 therein paralleling the hinge, and a catch in the form of a U-shaped member pivoted on the jamb member and adapted to swing into engagement with the notch and hold the locking member in locking position.

2. A door securer including a jamb member provided with spikes and a shoulder for engagement with a door jamb; a locking member hinged on the jamb member and having a notch therein adjacent the hinge, and a catch pivoted on the jamb member adjacent the shoulder and adapted to swing 95 into engagement with the notch and hold the locking member in locking position.

3. A door securer including a jamb member provided with spikes and a shoulder 100 for engagement with a door jamb; a locking member hinged on the jamb member beyond the shoulder, and a spring wire having its ends pivoted in the jamb member between said shoulder and the hinged connection with the locking member and adapted to swing into engagement with the locking member and hold it in locking position.

In testimony whereof I have signed my 105 name to this specification.

JOHN W. EMERSON.
